UNITED STATES PATENT OFFICE.

WILLIAM A. DAY, OF BELLINGHAM, WASHINGTON.

PIPE AND NUT WRENCH.

Application filed October 8, 1923. Serial No. 667,215.

To all whom it may concern:

Be it known that I, WILLIAM A. DAY, a citizen of the United States, and a resident of Bellingham, in the county of Whatcom and State of Washington, have invented a new and useful Improvement in Pipe and Nut Wrenches, of which the following is a specification.

My invention relates to improvements in pipe and nut wrenches, and one of the objects of my improvements is to provide a pipe and nut wrench having pawl and ratchet setting means, another object of my improvements is to provide a pipe and nut wrench having positive release means adapted to allow the jaws to separate when it is desired to relieve the wrench from a jammed position on the work between its jaws, and a further object of my improvements is to provide a pipe and nut wrench having quick action in setting on the work and of strong and durable construction and of simple design.

I attain these objects with the mechanism illustrated in the accompanying sheet of drawings, which forms a part of this application, and in which Figure 1 is a plan view of my wrench and Fig. 2 is a side elevation of Fig. 1.

Similar characters refer to similar parts throughout. Certain parts are broken away to show other parts hidden thereby.

More particularly: The wrench handle 3 has shank 4 to which it is joined by curved part a^3 . On the end of shank 4 is fixed jaw 5 in the plane of said handle and shank and, preferably, at an angle therewith. Said jaw 5 has slanting teeth inclined toward its point. On the upper end of jaw 5 are two ears 6 having a hole therethrough, at right angles to the plane of said handle and shank, in which is pin 7. Pin 7 serves as a pivot on which is mounted bar 8 for limited oscillation. Bar 8 has ratchet teeth on its side away from shank 4 slanting from pivot 7. The other end of bar 8 is pivoted to loop 10 by rivet 9. Loop 10 is mounted on handle 3 and shank 4 for reciprocation and has pin a^{10} therethrough to confine its movements to reciprocation. When loop 10 is in its full-line position it is normal to both shank 4 and bar 8 and retains said bar at its maximum distance from shank 4 and in its normal operative position. By moving loop 10 from its full-line to its dotted-line position at 10' in Fig. 2 it swings on pivot 9 and removes pin a^{10} from beneath said pivot when

bar 8 is free to assume its dotted-line position at 8'. Slideway 11 is mounted on loose jaw shank 13 and welded to bar 8 in proximity to ears 6 on fixed jaw 5, and it has a curved seat a^{11} into which said rounded ears bear. Loose jaw 12 has shank 13 at right-angles therewith, by preference. Said jaw has ratchet-form teeth on its face slanting from its tip. Shank 13 is mounted for reciprocation in slideway 11, and it has enlargement 14 to which is fastened slideway a^{14} in which is mounted bar 8 for reciprocation. This construction holds bar 8 beneath and parallel with shank 13 which is free to slide thereon. Bore 15 is made in enlargement 14 from the bottom of shank 13 to near its top where the diameter of said bore is reduced to provide a hole in which the pawl tail 16 is mounted for reciprocation. Pawl head a^{16} is mounted in the larger part of said bore for reciprocation and has a plurality of teeth b^{16} which engage with ratchet teeth a^8 . A spiral spring 17 is mounted on tail 16 in bore 15 and reacts between the pawl head a^{16} and shank 13, and it serves to retain teeth b^{16} in engagement with the teeth of bar 8. Two ears 18 extend upward from enlargement 14 and they have a hole therethrough in which is pin a^{18} . Said pin serves as a pivot for thumb lever 19. The rear end of 19 is a tooth a^{19} and is engaged in a notch in pawl tail 16. When 19 is depressed teeth b^{16} are withdrawn from engagement with ratchet a^8 against pressure of spring 17 and shank 13 is free to move to withdraw jaw 12 from jaw 5. But because of the inclined backs of teeth a^8 and b^{16} jaw 12 is easily caused to approach jaw 5 by pressure on said loose jaw toward said fixed jaw. With the described construction it readily appears that jaw 12 is held in its full-line position facing jaw 5 when loop 10 is in its full-line position. But when loop 10 is turned to 10' jaw 12 also moves to 12' and the former distance between said jaws is increased.

In operation: Jaw 12 is shoved away from jaw 5, while thumb lever 19 is depressed, to permit the work to enter about one half way up between said jaws. Then jaw 12 is forced to bear on the work by shoving it toward jaw 5. The wrench is now properly engaged with the work and is used till the desired end is attained, or till the jaws become stuck on the work. This jamming of the work in the jaws is easily relieved by swinging loop 10 to position 10' when the jaws

spread and the wrench is free to be removed from the work or to be reset thereon for further operations.

Having thus disclosed my invention, what 5 I claim as new and desire to secure by Letters Patent is,—

1. In a wrench in combination, a handle and a handle shank having a fixed jaw on the end thereof, slideways fastened to said handle shank, a loose jaw and a loose-jaw shank in the plane of said fixed-jaw shank when said jaws face each other in operative relation, a bar between said shanks retained in said slideways proximate to and parallel with 10 said loose-jaw shank, reciprocable thereon, having ratchet teeth on its side next to said loose-jaw shank, one end of which is pivoted to said fixed jaw and the other end of which is pivoted to a loop, a loop pivoted to 15 said bar and mounted on said handle shank whereby said jaws are retained in operative relation when said loop is normal to said bar but are allowed to separate a short distance 20

when said loop is turned on said pivot to an oblique position relative to said bar, and a 25 spring-pressed pawl mounted in said loose-jaw shank engageable with said ratchet teeth in said bar whereby said jaws are retained from separating but allowed to approach each other. 30

2. In a wrench in combination, a handle, a fixed jaw on one end of said handle, a movable jaw facing said fixed jaw in operable relation, a shank fixed to said movable jaw in the plane of said handle, a bar between 35 said shank and handle in the plane thereof and pivoted to said fixed jaw having slideable engagement with said shank, controllable means adapted to retain said bar at a fixed point in oscillation, and means adapted to retain said shank at different points from sliding further outward on said bar whereby said jaws are either retained at variable distances apart or permitted to increase their relative angularity as desired. 40

WILLIAM A. DAY.
